JOURNAL BOX

Glenn F. Couch, Rochester, N. Y., assignor to The Symington Company, New York, N. Y., a corporation of Maryland

Application November 16, 1931, Serial No. 575,393.

7 Claims. (Cl. 308—47)

This invention relates to journal boxes and, more particularly, to lids for closing journal boxes.

The principal object of my invention, generally considered, is to provide an articulated lid comprising a cover member or lid proper, a spring retainer, hood or spider, an actuating lever, and resilient means for urging said lever into engagement with the hinge lug of an associated box for holding the lid in open or closed position.

Another object of my invention is the provision of an articulated journal box lid comprising a spring retainer with a cover and a lever pivoted thereto at different points, and spring means with one end engaging the free end of the lever and the other engaging the retainer adjacent the pivotal connection with the cover, the pivotal connection between the retainer and the cover, if desired, comprising a pivot pin with a resilient or rubber bushing thereon and in engagement with an apertured lug on the cover for deadening vibration between the parts.

A further object of my invention is the provision of a journal box lid, the lower end of which is extended below a part normally engaging the lower edge of the journal box opening and formed with a rearwardly opening pocket adapted to receive a packing hook.

Other objects and advantages of the invention relating to the particular arrangement and construction of the various parts will become apparent as the description proceeds.

Referring to the drawings illustrating my invention, the scope whereof is defined by the appended claims:—

Figure 1 is a front elevational view of a journal box lid made in accordance with one embodiment of my invention, a portion of the hood thereof being broken away to more clearly illustrate the associated spider and lever.

Figure 2 is a side elevational view of the lid shown in Figure 1.

Figure 3 is a vertical sectional view on the line 3—3 of Figure 1, looking in the direction of the arrows.

Figure 4 is a fragmentary detail showing an elevational view of the packing hook pocket adjacent the lower end of the lid, approximately as shown in Figure 1.

Figure 5 is a vertical sectional view on the line 5—5 of Figure 4, looking in the direction of the arrows.

Figures 6 and 7 are views corresponding, re-

spectively, to Figures 4 and 5, but showing a modification.

Figures 8 and 9 are views corresponding, respectively, to Figures 1 and 3, but showing another embodiment of my invention.

Referring to the drawings in detail, like parts being designated by like reference characters, and first considering the embodiment of my invention illustrated in Figures 1 to 5, inclusive, there is shown a fragmentary portion of a journal box 1 provided upon its roof or top wall 2 adjacent the forward or outer edge 3 thereof with a hinge lug 4 which is apertured, as indicated at 5, to receive a hinge pin or pintle 6 for connecting the articulated lid or lid assembly 7 thereto. Said lug is further provided with faces 8 and 9 by which, through the cooperation of parts hereinafter described, the lid assembly 7 is maintained in either closed or open position. Said lid assembly comprises a cover or closure portion 10, a spring retainer or spider 11, a lever or lid-actuating member 12, in the form of a simple or generally straight, as distinguished from a bell crank, lever, and a spring or resilient means 13 for energizing said lever.

The cover or lid proper 10 is preferably formed as a substantially flat, suitably reinforced plate, the marginal edges 14 of which are adapted to overlie the marginal edges of the journal box opening 15. The lower end of the cover 10 is desirably extended below the lower edge of the journal box, as indicated at 16, and formed with a rearwardly opening pocket 17 defined by a rearwardly extending flange 18 and formed by upwardly embossing the lower extension of the lid, as shown most clearly in Figures 3 and 5. In order to guide an associated packing hook, the lower edge of the journal box lid is formed with a notch or groove 19.

The peripheral edge of the cover or lid proper 10 is rigidified by flanges 20 which overlie the box at the sides and upper edge of the opening. At the hinge lug, where the overlying flange is necessarily omitted, as shown most clearly in Figure 3, the strength of the lid is maintained by a similar outstanding flange 21 substituted for the overlying flange. The outer face of the lid proper 10 is formed with an outstanding apertured lug 22 receiving a pivot pin 23 which normally extends through correspondingly apertured lugs 24 on the retainer or spider 11 for pivotally connecting the spider and cover. The pivot pin 6 which connects the lid assembly to the box does so by passing through the hinge lug 4 with its outer ends received in correspondingly

apertured lug portions 25 on the spider. The pivot pin 6 is normally retained in position by the overlying side portions 26 of the hood portion 27 of the lid 10.

- 5 The spider 11 is formed generally as two side portions 28 which flare away from each other adjacent the upper ends, said upper ends receiving the pivot pin 6, and the lower ends receiving the pivot pin 23, as previously explained.
- 10 Adjacent the apertured lugs 24, the side portions 28 are connected by a transverse portion 29 which is preferably concave inwardly to provide a seat for the coils 30 of the torsion actuating spring 13. The upper portions of the side members 28 of the spider are desirably connected and rigidified by a second transverse portion 31.

15 The actuating lever 12 desirably has outstanding trunnions 32 pivotally mounted in inwardly and upwardly opening bearings 33 formed adjacent the upper ends of the side portions 28 of the spider 11, said trunnions preferably having flattened sides 34 so that they may be inserted in place in the slots 35 in the bearings 33 of the spider when the lever 12 is positioned in other than normal position, as will be understood. The lever 12 is desirably rigidified by side flanges 36 and formed with an outstanding lug 37 over which the loop portion 38 of the torsion spring 13 hooks when assembled, as shown most clearly in Figure 3.

20 In order to prevent loss or undesired removal of the pivot pin 23, the spider desirably has portions 39 extending beyond the apertured lugs 24 and notched, as indicated at 40, to provide seats for the lower ends of the torsion spring 13, said notches being so disposed that the ends of the spring 13 are held in position adjacent the ends of the pin 23 so as to be engaged upon axial movement of said pin to hold the latter in place.

25 From the foregoing disclosure, it is thought the manner of assembly and the operation of the lid will be apparent. It might be added, however, that the lever 12 is inserted and assembled with respect to the retainer 11 when the flattened sides 34 are disposed parallel to the sides of the slots 35 in the retainer bearings 33, that is, when the lever is disposed substantially 90° from the position shown in Figure 3. After assembly of the lever with the retainer or spider 11, the pivot pin 30 23 is desirably positioned to pivotally connect the spider and lid proper. The spring 13 is then positioned so that the lower ends thereof serve as retainers for the pin 23, as shown most clearly in Figures 1 and 3, the upper end of said spring hooking over the lug 37 of the lever 12. It will be seen that when the parts are assembled, as shown, for example, in Figure 3, the flange 21 performs the double function of rigidifying the upper edge of the lid adjacent the hinge lug 4 and acting as a stop for the lever 12 after the spider is assembled with respect to the cover, the clearances being such that the spider and assembled lever can be inserted in place with respect to the cover 10 before the pin 23 is positioned. After 40 assembly, it will be understood that the spring 13 urges the lever against the hinge lug 4 and the faces 8 and 9 thereof to alternately hold the lid assembly 7 in either closed or open position.

45 70 Referring now to the embodiment of my invention illustrated in Figures 6 and 7, a slightly modified form of packing hook pocket 17a is disclosed in which the flange 18a defining the same is extended rearwardly beyond the inner surface of the lid 10a and the lid is, therefore, not necessarily

5 embossed outwardly to the extent of the first embodiment. The lower edge of the lid is formed with a notch 19a for guiding the packing hook, as in the previous embodiment. Except as specifically described in connection with the present embodiment, the same may correspond with that of the preceding embodiment, the lid reinforcement, however, being illustrated as slightly different.

10 Referring now to the embodiment of my invention illustrated in Figures 8 and 9, a construction is there disclosed involving an articulated lid or lid assembly 7b comprising a cover or lid proper 10b, a spring retainer or hood 11b, an actuating lever 12b, and an energizing spring 13b. As in 15 the previous embodiment, the retainer is pivoted to a hinge lug 4b by a pivot pin 6b, and the lower end of the retainer 11b receives a pivot pin 23b passing through an apertured lug 22b extending from the outer face of the lid 10b, a resilient or 20 rubber bushing 41 being mounted on the pin 23b and disposed between the same and the lug 22b for deadening vibration and minimizing wear between the retainer and lid.

25 As in the preceding embodiment, a torsion spring 13b is employed, the coils of which seat on the retainer, which, in the present embodiment, is also a hood, and the lower ends of which engage seats on said retainer, but do not, as in the preceding embodiment, act as retaining means 30 for the pin 23b, which is shown as having its ends riveted over, or one end headed and the other riveted over, as indicated at 42. The upper or looped end 38b of the spring 13b desirably hooks over a lug 37b on the lower end of the lever 12b, which lever, 35 as in the previous embodiment, is desirably reinforced by side flanges 36b.

40 The lever 12b of the present embodiment is not formed with outstanding trunnions, as in the preceding embodiment, but rather with a beaded upper edge 32b forming trunnion means engaging confining and bearing lugs 43, 44, 45 and 46 on the retainer 11b. The beaded upper edge 32b is of such form that it may be inserted in place when the lever is moved to abnormal angular position 45 so that it lies adjacent and substantially parallel to the outer wall 47 of the hood 11b, and it is subsequently interlocked therewith upon movement to the normal position shown in Figure 9.

45 50 The assembly and operation of the articulated lid in the present embodiment, as will be understood, is similar to that of the lid in the preceding embodiment, except that the matter of the assembly of the spring 13b is simplified because said spring does not also serve as a retainer for the pin 55 or rivet 23b. For this reason, the spring is adapted to be placed under a greater amount of initial tension than in the first embodiment. Except as specifically described in connection with the present embodiment, the same may correspond with 60 the embodiment of Figures 1 to 5, inclusive, it being understood, however, that the retainer of the present embodiment functions as a hood, and the cover is unprovided with an integral hood. It will also be understood that the upper edge of the 65 lid proper 10b functions as a limit stop for the lever 12b of the present embodiment, rather than an outstanding flange on said upper edge.

70 75 From a consideration of the foregoing, it will be seen that I have devised an improved articulated lid for journal boxes involving movably connected cover, spring retainer and lever portions, with resilient means for urging the lever into operative engagement with the hinging lug of an associated box.

Although I have described preferred embodiments of my invention, it will be understood that modifications may be made within the spirit and scope of the appended claims, and that the terms and expressions which I have employed are used as terms of description and not of limitation.

I claim:—

1. In combination, a journal box having a hinge lug and a lid assembly mounted thereon and comprising a spring retainer with a cover and a generally straight lever pivoted thereto at different points, and spring means with one end engaging the free end of the lever and the other end engaging the retainer adjacent the pivotal connection with the cover.

2. In combination, a journal box having a hinge lug, a lid assembly mounted thereon and comprising a lid proper, spring retainer means respectively pivoted at its ends to the hinge lug and lid proper, and spring means disposed between said retainer means and lid proper, said spring means comprising a lever pivoted to the spring retainer, and a torsion spring with an upper loop portion engaging said lever, intermediate coil portions supported on said retainer, and lower end portions engaging lower abutment portions on said retainer.

3. In combination, a journal box having a hinge lug, and a lid assembly for closing the outer opening in said box, said assembly comprising a closure member with a hood outstanding from the front face thereof and adapted to fit over said lug, a spider received between said closure member and hood, a lever pivoted to said spider adjacent its upper end, a pivot pin connecting the lower end of said spider to said closure member, a torsion spring with an intermediate portion seated on said spider, an upper portion engaging said lever for actuating the same, and lower portions engaging said spider and lying adjacent opposite ends of said pivot pin for preventing undesired removal thereof.

4. In combination with a journal box having a hinge lug, an articulated lid pivotally connected thereto, said lid including a hood, a cover and a lever, said lever being pivotally connected to the hood adjacent the upper ends of said mem-

bers, a pin extending through the lower portion of said hood and an intermediate portion of said cover, a resilient bushing mounted on said pin for reducing wear therebetween, and a spring for actuating said lever, said spring having an intermediate portion mounted on said hood, an upper portion engaging the lever adjacent its lower end, and lower portions engaging said hood.

5

5. A journal box lid comprising a spring retainer with a cover and a lever pivoted thereto at different points, and spring means involving an intermediate portion seated on the retainer, one end engaging the free end of the lever and the other end engaging the retainer adjacent the pivotal connection with the cover.

10

6. In combination, a journal box having a hinge lug and a lid assembly for closing the outer opening in said box, said assembly comprising a closure member, a spring retainer, a lever pivoted to said spring retainer adjacent its upper end, means movably connecting the lower end of said spring retainer to said closure member, a torsion spring with an intermediate portion engaging said spring retainer, the upper portion engaging said lever for actuating the same, lower portions 20 engaging said spring retainer and lying adjacent opposite ends of said pivot pin for preventing undesired removal thereof, and means pivotally connecting said closure member and spring retainer to said box.

25

7. In combination with a journal box having a hinge lug, an articulated lid pivotally connected thereto, said lid including a spring retainer, a cover and a lever, said lever being pivotally connected to said spring retainer adjacent the upper portion of said lid, a pin extending through the lower portion of said spring retainer and an intermediate portion of said cover, a resilient device mounted on said pin and engaging the surrounding portion of said spring retainer, and a spring for actuating said lever, said spring having intermediate portions mounted on said spring retainer, an upper portion engaging the lever adjacent its lower end, and lower portions engaging abutments 30 on said spring retainer.
